AUTOMATIC ADAPTER UNIT FOR TELEPHONE
3,319,003
INSTRUMENTS
Joseph H. Prager, North Hollywood,
forty percent to Nichimen Co., Ltd., Calif, assignor of
corporation of Japan
Filed Nov. 8, 1963, Ser. No. 322,432
8 Claims. (Cl. 179—1)

The present invention relates generally to the art of communication, and is more particularly concerned with an adapter unit for converting a conventional telephone auxiliary apparatus. As exemplary of a variety of types of auxiliary apparatus which may be utilized, the adapter unit of the present invention may be utilized, and recording devices may be mentioned particularly.

Considered in its broad concept, the present invention has for an object the provision of a self-contained adapter unit which may be removably installed on a telephone instrument of a publicly owned telephone system, without violation of presently established rules and regulations. A further object is to provide a separate independent adapter unit which may be removably attached to a conventional dial type telephone instrument to provide all the necessary operative functions required to utilize the auxiliary apparatus, without the necessity of utilizing physically connected tie-in wires with the telephone instrument or the communication line circuit.

Still another object is to provide an adapter unit of attractive and pleasing appearance, which may be removably seated on the telephone cradle in proper relationship therewith to dispose devices in the adapter in proper operative relationship with respect to certain components of the telephone instrument, and wherein the adapter unit forms the support for the handset of the telephone instrument.

Further objects of the invention will be brought out in the following part of the specification, wherein the detailed description is for the purpose of fully disclosing the invention without placing limitations thereon.

Referring to the accompanying drawings, which are for illustrative purposes only:

FIG. 1 is a perspective view showing the adapter unit of the present invention as being applied to a conventional telephone instrument;

FIG. 2 is an enlarged plan view of the adapter unit;

FIG. 3 is a transverse section through the unit to show the cooperative relationship between certain of the components therein, taken substantially on line 3—3 of FIG. 2;

FIG. 4 is a longitudinal section taken substantially on line 4—4 of FIG. 2, certain of the parts being shown in

are provided with activating switchmeans operable by a pair of spaced actuating pins (not shown) on the cradle. These pins are engageable by the handset when it is placed on the cradle, the weight of the handset serving to move the activating switch to a non-activating position, and when the handset is removed from the cradle, the activating switch automatically moves to an activating position in the conventional dial type telephone instrument, a number is dialed through the use of a manually operating disc. It is also generally known that it is possible with the handset removed from the cradle, to dial a number by successively depressing the activating switch pins so as to produce the grouped pulses of a desired number. As will hereinafter be explained more fully, the principle is utilized in the adapter of the present invention for accomplishing automatic dialing operations, connecting and disconnecting the telephone with automatically answering and recording use with auxiliary devices.

The adapter of the present invention comprises a like housing, as generally indicated by the which may be molded or otherwise formed of other suitable material to provide an open structure containing a central platform portion spaced cradle forming supports 14 and 15 for the telephone handset in lieu of the instrument. As thus supported, the earpiece of the 11 will be positioned below the and earpiece 11 will be positioned in the instrument. The shell-like housing 12 is and sides of the platform portion 13 and lying end extensions or wings 16 and 17 edges to generally interfittingly connect of the adjacent wall structure of the structure B, and with the central panel or platform 19 arranged to overlie wall wall 19 with a front panel or wall may be removably applied to instrument and latchingly secured cradle structure. As thus mounted on the cradle structure. A push-button 21 is mounted on the cradle structure. As shown in FIG. 4, the handset seated on the cradle so as to be engaged and by the outermost end of the central portion of an pulsing lever 23 pivot at its outermost end on a pivotal axis 24, the outermost end with a solenoid 26 an actuating coil 27.

The elongate base 22 so positioned having switch pins 21 instrument, as at its most end of the 22, this spring 20 towards its end.

form; electrical indicating means on the form portion having an energizing circuit operable switch for controlling said circuit being operable from the front of said platform.

5. An adapter unit for a dial telephone set and receiving cradle therefor, the cradle being arranged with an activating switch control pin, comprising: a housing of shell-like construction adapted to removably seat on the telephone cradle, said housing having a central platform portion arranged in the seated position to overlie the cradle; the cradle switch pin and removable phone handset thereon; housing end portions extending from said central portion adapted to respectively adjacent earpiece and mouthpiece ends of the supported telephone handset; means operable under the weight of the handset on said platform portion to pick up said pin to actuate said switch to a non-activating position; circuit controlling contacts actuating the operation of said means; and means operable means and electrically energizable to independently actuate said switch to an activating position while the handset is on the platform.

6. An adapter unit for a dial telephone set and receiving cradle therefor, the cradle being arranged with an activating switch control pin, comprising: a housing of shell-like construction adapted to removably seat on the telephone cradle, said housing having a central platform portion arranged in the seated position to overlie the cradle; the cradle switch pin and removable phone handset thereon; housing end portions extending from said central portion adapted to occupy positions respectively adjacent mouthpiece ends of the supported telephone handset; means operable under the weight of the handset on said platform portion to normally move said pin to a non-activating position; pick up means having inductively coupled contacts; a ringing device; and means acting on said contacts and electrically energizable to indicate said switch to an activating position while the handset is on the platform.

7. An adapter unit for a dial telephone set and receiving cradle therefor, the cradle being arranged with a telephone activating switch, comprising: a housing of shell-like construction adapted to removably seat on the telephone cradle.

in the seated position; a movable end portion adapted to occupy an earpiece and mouthpiece position; a movable engagement member in the housing; a compression spring member in the housing; and a handset engagement member in the housing; and means for energizing the handset engagement member to move the handset into a non-activating position; and means for energizing the handset engagement member to move the handset into an activating position.

having a handset being arranged in, comprising: a central platform portion of the telephone cradle oppositely extending to occupy positions respectively adjacent mouthpiece ends of the central portion; using in a seated position a central portion of the telephone cradle; means operable on said platform for actuating said switch to a non-activating position on said weight; and means operable to independently actuate said switch to a non-activating position.
